GARMENT HANGER COVER

Henry C. Ruen, Detroit, Mich., assignor to Cleaners Hanger Company, Detroit, Mich., a corporation of Michigan

Application December 27, 1937, Serial No. 181,892
Renewed February 4, 1939

16 Claims. (Cl. 223—98)

This invention relates to covers for garment hangers and particularly to paper covers for wire garment hangers of a common triangular type.

The primary purpose of such covers is to prevent such direct engagement of a cleaned garment with a wire hanger as might cause soiling of the garment, and they further serve to carry any desired printed matter. Since such covers are ordinarily applied by untrained employees and may not materially increase the cost of garment hangers, it is desirable that they be applicable as simply and rapidly as possible.

An object of the invention is to form a garment hanger cover with three flaps respectively adapted to be folded over the respective sides of the hanger body, said flaps so meeting or adjoining as to adapt them to be readily interengaged and secured in their positions of use.

Another object is to marginally form the front wall of a garment hanger cover with a plurality of flaps serving to jointly form the rear wall, one of such flaps being foldable about the mid portion of the lower bar of a triangular wire garment hanger, the front and rear walls having free lower portions serving to cover the remaining portions of said bar.

A further object is to adapt a garment hanger cover having flaps as above described, to be blanked in quantities from a sheet of paper with a minimum of waste by so relatively locating and proportioning said flaps, that one such flap of any blank may be struck out from between the other two flaps, as formed on another blank.

A further object is to adapt the three described flaps, when folded to form a cover, to be interengaged by a single operation.

These and various other objects are attained by the construction hereinafter described and illustrated in the accompanying drawing, where-

40 in:

Fig. 1 is a front view of the improved cover, as applied to a garment hanger.

Fig. 2 is a rear view of the same.

Fig. 3 is an enlarged vertical sectional view, 45 taken on the line 3—3 of Fig. 1.

Fig. 4 is an enlarged vertical sectional view taken on the line 4—4 of Fig. 2.

Fig. 5 is a view of a paper blank from which the cover is formed.

50 In these views, the reference character 1 designates the front wall of the improved cover, such wall having substantially the shape of an isosceles triangle in conformity with the triangular body 2 of a common type of wire garment hanger. Integrally projecting from said wall,

at its downwardly divergent lateral margins, is a pair of flaps 3, substantially coextensive with said margins and adapted to be folded over the sides of the hanger 2. When so folded, said flaps adjoin at the mid portion of the wall 1 and conform to such wall except as regards its lower mid portion. That is to say, said flaps project downwardly a slight distance below the lower member of the hanger, as does the wall 1, said flaps and wall thus coacting to cover the 10 side members of the hanger and also the bottom member thereof, with the exception of its mid portion, as clearly appears in Fig. 2. To cover such mid portion, a relatively small flap 4 approximately triangular in shape, integrally projects from the 15 wall 1 at the mid portion of its lower margin, such portion being upwardly offset to adapt the flap 4 to be folded about the bottom member of the hanger 2. When thus folded, the flap 4 overlaps the flaps 3, and by the use of an adhesive, 20 may serve to interconnect the same. Preferably the interconnection is established by a sticker 5 overlapping the three flaps.

An important feature of the invention is the employment of a blank for forming the described 25 cover, minimizing waste in forming a quantity of the blanks from a sheet of paper or the like. Thus, as best appears in Fig. 5, the small flap 4, projecting downwardly from the mid portion of the wall or panel 1, is shaped to approximately 30 conform with the reentrant opening 6 formed between the flaps 3, and such opening and the small flap are both bisected by the median line between the blank extremities. It follows that a major portion of the flap 4 of one blank may be 35 struck out of the opening 6 of an adjacent blank, in feeding a sheet of material to the blank-forming dies (not shown). The resulting avoidance of waste is highly desirable in quantity production of the blanks. Waste is further minimized 40 by similarly forming the flaps 3 with edges 7 diagonally extending from the margins of the opening 6 to the outer edges of said flaps, since this reduces the vertical dimension of the blank. Thus cutting away the inner corners of the flaps 45 3 produces a triangular opening between the lower portions of said flaps when they are folded, as in Fig. 2, but this is not objectionable since the flap 4 covers and conceals such opening.

To facilitate application of the described cover 50 to a garment hanger, fold lines 8 may be preformed on the blank at the junctures of its several flaps with the panel 1.

It will be noted that the adjoined edges of the flaps 3 (see Fig. 2) diverge at an acute angle as 55

they extend upwardly from the flap 4. This permits the upper mid portion of the sticker 5 to adhere to that small portion of the front wall which is exposed between said edges, whereby 5 the sticker forms a reinforcing connection between the front and rear walls of the cover. Engagement of the sticker with the front wall, as described, is further desirable in counteracting any tendency of the garment hanger and cover 10 to shift relatively in a lateral direction to a material extent.

A primary advantage of the described cover lies in its simplicity and its adaptability to be very quickly applied to a garment hanger by unskilled 15 labor.

While printed matter may be applied to either or both faces of the cover, the wall 1 is particularly suited to receive such matter, since its surface is unbroken.

20 It is to be noted that access may be readily had to the lower span of a hanger fitted in the described cover, in case it is desired to hang a belt or the like on such bar.

The invention is presented as including all such 25 modifications and changes as come within the scope of the following claims.

What I claim is:

1. A cover for a triangular garment hanger comprising a substantially triangular wall for 30 engaging at one side of a garment hanger having an upstanding support, and three flaps respectively projecting from the respective margins of said wall for jointly forming a wall engageable at the other side of the garment hanger, said 35 flaps being adapted for folding over the corresponding sides of the garment hanger and two of said flaps being adapted, when folded to marginally adjoin each other adjacent to the mid portion of said wall, the third flap being proportioned to lap the adjoined margins of the other two flaps, the cover having an opening to accommodate said upstanding support.

2. In a cover for a triangular garment hanger as set forth in claim 1, a common means for interconnecting the three flaps in wall-forming relation.

3. In a cover for a triangular garment hanger as set forth in claim 1, a sticker interconnecting all three flaps in wall-forming relation.

4. A cover for a triangular garment hanger as set forth in claim 1, the third flap being proportioned to fold over only the mid portion of the corresponding side of the garment hanger and the other two flaps and said wall being proportioned to extend beyond and jointly substantially cover the remaining portions of said corresponding side.

5. A cover for a triangular garment hanger having a pair of downwardly divergent members 60 and a bottom member, said cover comprising a substantially triangular wall for engaging at one side of a garment hanger, a pair of similar flaps integrally projecting from and approximately co-extensive with downwardly divergent margins of said wall and adapted to be folded over corresponding members of the hanger, the bottom margin of said wall having a reentrant mid portion, and a third flap integrally projecting from such mid portion, to be folded over the bottom member of the hanger, the three flaps being shaped and proportioned to adjoin in proximity to the mid portion of said wall, and the two similar flaps being proportioned to marginally coat 70 with marginal portions of said wall to cover the

bottom member of the garment hanger at each side of the bottom flap.

6. A blank for forming a cover for a triangular garment hanger, such blank comprising a panel having approximately the shape of an isosceles triangle for engaging at one side of a garment hanger, a pair of spaced similar flaps, integrally projecting from the sides of said panel and adapted to be folded over two sides of the garment hanger, and a third flap projecting downwardly from the panel to be folded over the third side of the garment hanger, and proportioned and positioned relatively to the other two flaps, to be partially struck out of another similar blank from between the two similar flaps thereof, in forming both blanks from a single sheet of material.

7. A blank for garment hanger cover purposes, formed of sheet material and having an opening extending from its margin toward its center and producing a pair of similar flaps, and having a third flap projecting from its margin at a point opposite to said opening and approximately conforming in proportions and shape to such opening, whereby the third flap of one blank may be partially struck out of said opening of another, the two similar flaps being foldable along divergent lines to conform to the sides of a triangular garment hanger, and the third flap being foldable to conform to the bottom member of such a hanger, the three flaps being thus adapted to form a wall opposed to a wall formed by the remaining portion of the blank.

8. A cover for a garment hanger having approximately the shape of an isosceles triangle, said cover comprising a substantially triangular front wall for engaging at one side of a garment hanger, a pair of flaps integrally projecting from opposite lateral margins of said wall and folded over the lateral members of the garment hanger to jointly form a rear wall of the cover, a gap being formed between said flaps when so folded, and a sticker interconnecting said flaps and secured to the portion of the front wall exposed through said gap.

9. A cover as set forth in claim 8, further formed with a flap integral with a lower margin of said front wall, and folded over the bottom member of the garment hanger and engaged and held by said sticker.

10. A cover for a triangular garment hanger having an upstanding support, said cover comprising a substantially triangular wall for engaging at one side of a garment hanger, and three flaps respectively projecting from the respective margins of said wall and folded to jointly form a wall engageable at the other side of the garment hanger and adjoining each other adjacent to the mid portion of said wall, and a member overlapping and interconnecting the three flaps, the cover having an opening to accommodate said upstanding support.

11. A cover for a garment hanger having approximately the shape of an isosceles triangle, said cover comprising a substantially triangular front wall for engaging at one side of a garment hanger, a pair of flaps integrally projecting from opposite lateral margins of said wall and folded over the lateral members of the garment hanger to jointly form a rear wall of the cover, a gap being formed between said flaps when so folded, and a common means for interconnecting said flaps and securing them within said gap to the front wall.

12. A cover for a garment hanger having approximately the shape of an isosceles triangle,

and including upper and lower garment-receiving elements, said cover comprising front and rear walls and a flap formed integrally with a lower margin of one such wall, said flap being 5 upwardly folded and secured to the other wall to retain a hanger in the cover, the cover having a bottom opening at each side of said flap, whereby access is afforded to said lower element of the hanger, said walls downwardly extending 10 beyond the fold of said flap, whereby said fold may closely adjoin the lower element of the hanger, and such element may lie fully between said walls at each side of the flap.

13. A cover for a garment hanger having approximately the shape of an isosceles triangle, 15 and including upper and lower garment-receiving elements, said cover comprising front and rear walls and a flap formed integrally with a lower margin of one such wall, at the mid portion of 20 such margin, said flap being upwardly folded in close proximity to said lower element of the garment hanger and exteriorly secured to the other of said walls to retain the hanger in the cover, the cover having similar bottom openings at 25 each side of said flap affording access to the lower element of the hanger.

14. A cover for a triangular garment hanger having an upstanding support, said cover comprising a substantially triangular wall for engaging at one side of a garment hanger, and three 30 flaps respectively projecting from the respective margins of said wall for jointly forming a wall engageable at the other side of the garment hanger, said flaps being adapted for folding over the corresponding sides of the garment hanger 35 and two of said flaps being adapted, when folded to marginally adjoin each other adjacent to the mid portion of said wall, the third flap having portions lapping the other two flaps and the

three flaps having mutually adjoined marginal portions, and means adhesively interconnecting the three flaps, engaging their mutually adjoined marginal portions, the cover having an opening to accommodate said upstanding support. 5

15. A cover for a triangular garment hanger having an upstanding support, said cover comprising a substantially triangular wall for engaging at one side of a garment hanger, and three flaps respectively projecting from the respective 10 margins of said wall for jointly forming a wall engageable at the other side of the garment hanger, said flaps being adapted for folding over the corresponding sides of the garment hanger and two of said flaps being adapted, when folded 15 to marginally adjoin each other adjacent to the mid portion of said wall, the third flap overlapping the other two, and means for adhesively securing the third flap to one of the other two flaps, 20 the cover having an opening to accommodate said upstanding support. 20

16. A cover for a triangular garment hanger having an upstanding support, said cover comprising a substantially triangular wall for engaging at one side of a garment hanger, and three flaps respectively projecting from the respective 25 margins of said wall for jointly forming a wall engageable at the other side of the garment hanger, said flaps being adapted for folding over the corresponding sides of the garment hanger and two of said flaps being adapted, when folded 30 to marginally adjoin each other adjacent to the mid portion of said wall, the third flap overlapping the other two, and means for securing the third flap in its overlapping position, the cover 35 having an opening to accommodate said upstanding support. 30
